GARMENT

Frances R. McAbee, Westport, Conn., assignor to
McAbee Industries, Incorporated, Westport,
Conn., a corporation of Connecticut

Application May 19, 1945, Serial No. 594,729

2 Claims. (Cl. 2—73)

1

This invention relates to new and useful improvements in ladies' garments, and has for its principal object the provision of an improved body garment which may be embodied in a slip, gown, or dress, and which has certain structural features which improve the fit of the garment on the body of the wearer, resulting in an extremely comfortable garment and one which will not twist or ride up when the wearer sits down.

The garment of the present invention embodies the best features of garments cut largely or wholly on the bias, including particularly the comfortable wearing qualities of such a garment and the durability of the seams. It also retains, however, the fine fitting qualities of the straight-cut slip when the wearer is standing, and the non-riding qualities of such a slip when the wearer sits down.

The bias-cut slip of conventional construction accommodates the increased girth of the wearer when she sits down, by expanding circumferentially, although such expansion reduces the effective length of the garment, causing it to pull downwardly on the shoulder straps, and ride upwardly over the knees. In the garment of the present invention, the relationship of the parts is such that the increase in circumference of the middle and waist portion, due to sitting down, does not foreshorten the garment vertically.

Another important object of the invention is to provide a garment which readily passes over the shoulders of the wearer, and also snugly fits the waist portion of the wearer when she is standing. Many persons are so proportioned as to have relatively wide shoulders compared with their middle dimensions, and to enable a well-fitting garment to pass the shoulders, side openings closeable by slide fasteners, buttons and the like must be resorted to. The present garment passes the shoulders as readily as a full bias garment, but also hugs the waist portion closely at all times. Since the waist portion is snugly fitting, there is no need for a separate midriff blank which is sometimes inserted in garments that tend to have a loose-fitting midriff portion. These midriff blanks must almost of necessity be on the straight of the material relative to the front median line of the garment, which tends to lose all flexibility of the garment around the waist section.

The garment may be formed from two blanks of similar shape which are joined together along two adjacent edges to form a single vertical front seam, and along the two remaining vertical edges to form a single vertical rear seam. A dart of novel construction is formed on each side of the

2

garment extending from a point spaced from the front median line and just below the bust-encircling portion, through the under-arm section to the rear of the garment where it terminates at the rear vertical seam at or near the waist line. This dart shapes the bust portion of the garment, giving it the effect of a well-fitting brassiere, permits entire freedom of movement by the wearer, and causes the skirt portion of the garment to merge symmetrically into the waist portion. Inasmuch as each blank is cut horizontally from two-thirds to three-fourths of its width to form the edges, which when joined together, form this dart, each side blank may be formed in two pieces instead of a single piece without departing from the structure of the invention as defined by the appended claims.

The pattern is so arranged as to have a minimum of waste material in cutting, and the garment is further so formed as to make the task of grading the patterns for the size ranges a relatively simple one. Also, the sewing operation is relatively simple, particularly for the reason that the operator is required to handle only two blanks instead of six, eight, or even ten, as in conventional garments.

In the drawings:

Fig. 1 is a front and partial side elevation of a ladies' garment embodying the present invention.

Fig. 2 is a rear and partial side elevation of the same garment.

Fig. 3 is a broken side elevation of the upper or waist-encircling portion of the garment.

Fig. 4 is a plan view of a blank, two of which are used in forming the garment of the present invention.

Fig. 5 is a plan view of two blanks similar in contour to the blank of Fig. 4, but showing alternative means whereby the blank of Fig. 4 is formed from two pieces rather than one piece.

Two blanks 10 of the contour shown in Fig. 4 may be used in forming one embodiment of the garment of the present invention. Each blank 45 includes a lower curved edge 11 which forms the lower edge of the garment, and a substantially vertical, straight edge 12 which is somewhat concavely curved at its upper end, as shown at 13, such edge terminating at point 14. The blank further includes a short, downwardly-inclined edge 15, and a substantially straight, upwardly-inclined edge 16 which terminates at point 17 which is disposed at the front center of the upper edge of the garment. Continuing from point 17, there is a substantially straight edge 18

terminating at point 19, a concavely-curved edge 20 terminating at point 21, and a short, straight or concavely-curved edge 22 terminating at point 23 which is at the upper edge of the center back of the finished garment. Finally, the blank includes a downwardly-extending, substantially-straight edge 24, and another downwardly and outwardly-extending, substantially-straight edge 25 which terminates at point 26 where it intersects with the lower curved edge 11 at the lower edge of the center back of the garment.

Between the lower terminal 30 of edge 24, and the upper terminal 31 of edge 25, there is an inwardly-extending cut, and in forming this cut some of the material may be removed from the blank. The cut is thus defined by upper edge 34 and lower edge 35 which intersect at their inner ends at point 36. In cutting blank 10, the grain line of the material, shown at 39, should have substantially the relationship shown. This grain line may, of course, vary in certain sizes of the garment, although for most sizes the line indicated is preferable, and is substantially parallel with only one edge of the blank, namely, edge 18.

In forming the garment, two blanks 10 are first joined along edges 12 and 13 to form stitch line 40 which constitutes the front median line of the garment. A short, triangular dart over each bust is now formed. Broken lines 27 and 28 define the location of this dart. The material is folded downwardly to where point 30 coincides with point 41, and stitch line 42 is then formed. Next, edges 16 are joined together to form stitch line 43, which, when viewed from the front, is a continuation of stitch line 40. Edges 18, 20 and 22 in each blank 10 form the upper edge of the garment, and shoulder straps 45 are secured at their forward ends to points 18, and at their rear ends to points 21. Upper rear edges 24 are next joined together to form rear vertical seam 48, and lower vertical edges 25 are joined together to form vertical seam 49 which is a continuation of seam 48.

The contour of edges 34 and 35 in the transverse opening now will be considered. It will be noted that edge 34, which is concavely curved, forms the arc of a somewhat larger circle than does edge 35, which is likewise somewhat concavely curved. These edges are joined together to form stitch line 50. The contour of edges 34 and 35 will be varied, depending upon the particular size of the garment, and in some instances one edge or the other may have a greater curvature. Both edges are of substantially the same length, although if a garment having larger bust dimensions is required, edge 34 may be of greater length, and when the two edges are joined together, the longer edge 34 may be progressively fulled relative to edge 35. Conversely, if it is desired to make the bust portion relatively smaller and the midriff and hip sections proportionately larger, edge 35 may be of greater length than edge 34.

By forming edge 34 of a contour such that a line tangent to such edge substantially at its center is substantially at right angles to edge 24, a garment will be provided which fits the average figure, and the resulting stitch line 50, which is formed when edges 34 and 35 are joined together, is inclined downwardly from its upper terminal 36. The lower terminal of stitch line 50 at the center back seam is disposed at or near the waist line of the wearer. In the smaller sizes, this rear terminal may be somewhat above

the waist line, and in the larger sizes, it may be slightly below the waist line.

With further reference to the contours of edges 34 and 35, it may be said that for garments of the relatively smaller sizes, these edges may be more nearly straight for the reason that the wearer's hips are relatively small, and the upper back portion is relatively flat. In garments of larger sizes, however, the curve may be greater than that shown in Fig. 4. It will be appreciated, also, that the grain line of the material through the waist section in the finished garment depends upon the general angle of edges 34 and 35 relative to edge 24. If these edges are generally at right angles with edge 24, as is shown in Fig. 4, the resulting skirt is quite full, whereas if they are inclined more upwardly at their inner ends, the result is a somewhat tighter skirt. Also, the amount of material which is cut out to form edges 34 and 35 may vary in several instances. Generally speaking, it may be said that for the smaller sizes less material is cut out, whereas for the larger sizes a greater amount of material may be cut out.

The purpose of short dart 42 on each side of the bust portion is to cause the garment to cling to the body in the area intermediate the busts of the wearer. It will be readily appreciated that this desirable result is not achieved in conventional garments having the usual side seams, and no front and back central, vertical seams. Front seams 40 and 43 in the garment of the present invention give the desirable separation line in the bust-enclosing portions of the garment, and thus eliminate the need for a form-fitting brassière. Also of particular advantage is the fact that the front and rear seams form lines of fixed length, which effectively prevent the garment from riding up when the wearer sits down. Thus, although the garment is largely on the bias, it does not have the objectionable feature of the bias garment, causing the garment to shorten in the front and back when the wearer sits down, but, on the contrary, the present garment acts like a straight-cut garment under such conditions.

In Fig. 5, the blank used in forming each side of the garment is made in two pieces 10a and 10b, instead of one piece as shown in Fig. 4. When the two pieces are joined together along edges 60 and 61, a blank similar to that shown in Fig. 4 is formed. The primary advantage in this construction is that it enables one to utilize smaller pieces of material, and certain structural changes will result in the finished garment if the grain lines of the material are varied somewhat.

While two forms or embodiments of the invention have been shown and described herein for illustrative purposes, and the construction and arrangement incidental to two specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What I claim is:

1. A ladies' garment including attached waist and skirt portions and formed from a pair of similarly-shaped blanks, each formed from a plurality of pieces of material, two adjacent side edges of the blanks being joined together to form

a single, front vertical seam, and the two remaining side edges of the blanks being joined together to form a single, rear vertical seam, such seams lying, respectively, substantially along the front and rear vertical median lines of the garment, each blank including a curved lower edge forming the lower edge of the garment, the side edges, and upper edges which form the upper edge of the waist portion of the garment and which are formed with front and back, upwardly-inclined extensions, shoulder straps on each side of the garment secured at their opposed terminals to such extensions, each blank having a cut-out portion extending inwardly from the side edge at the rear of the garment to a point adjacent to, but spaced from, the vertical edge at the front of the garment, such cut-out portion lying in the lower waist-encircling section, the upper and lower edges of such cut-out portion being joined together to form a generally diagonal seam which extends from adjacent the front of the bust-enclosing section downwardly to the rear vertical seam.

2. A ladies' garment formed with attached waist and skirt portions and formed from a pair of similarly-shaped blanks of generally rectangular contour which are joined together along ad-

jacent edges to form front and rear vertical seams coinciding generally with the front and rear vertical median lines of the garment, means comprising shoulder straps extending over the shoulders of the wearer connecting the front and back of the upper edges of the blanks, each blank having a cut-out portion extending from the rear seam adjacent the waist line of the garment generally upwardly through the underarm section 10 of the garment to a point spaced from the front vertical seam, the opposed edges of such cut-out portion being joined together to form a dart which shapes the bust-enclosing portion of the garment, and short darts extending upwardly 15 from the front vertical seam over the bust-enclosing portions.
